UNITED STATES PATENT OFFICE

DONALD S. BARROWS, OF ROCHESTER, NEW YORK

RAILWAY TRUCK

Application filed February 23, 1928. Serial No. 256,331.

This invention relates to railway trucks and more particularly to the construction of the side frames, bolsters and associated parts whereby relative rocking is permitted between said frames and bolsters.

The principal object of my invention, generally considered, is the improvement in car trucks whereby such trucks have great flexibility for accommodating themselves to inequalities in the track and for relieving the members thereof from sudden and undue strains whereby the life of the truck is increased.

An object of my invention is the provision of railway trucks formed with side frames provided with bolster openings receiving springs and spring caps, a bolster supported on said spring caps and some of the engaging surfaces between the bolster and caps being curved to permit rolling or rocking between said bolster and frames in vertical longitudinal planes.

Another object of my invention is to provide an integral side frame formed with a bolster opening receiving bolster springs, said springs supporting a spring cap and a bolster supported on said cap, said cap being formed with column engaging flanges or guides and the bolster interlocked with respect thereto whereby said bolster may be free from column engaging flanges.

A further object of my invention is to provide a railway truck formed with side frames having bolster guide columns connecting intermediate portions of the tension and compression members thereof, springs supported on said side frames between said guide columns, spring caps supported on said springs, and a bolster supported on said spring caps and connecting said frames, said bolster being formed to interlock with said spring caps longitudinally and transversely and adapted to rock thereon for increasing the flexibility of the truck.

A still further object of my invention is to provide a built-up bolster formed with compression and tension members and end castings connected at the ends of said members by common rivets extending therethrough, said end castings being shaped to

either interlock with the associated side frames or with the spring caps thereof and when interlocked with said spring caps being preferably formed to permit rocking between said parts.

Other objects and advantages of the invention relating to the particular arrangement and construction of the parts will become apparent as the description proceeds.

Referring to the drawings illustrating my invention, the scope whereof is defined by the appended claims,

Figure 1 is a partial side elevation of a truck particularly showing the intermediate portions of the side frame compression and tension members, the connecting bolster guide columns, the end of the bolster and the associated connecting parts.

Figure 2 is a transverse sectional view of the frame shown in Fig. 1, the associated bolster and spring cap being shown in side elevation.

Figure 3 is a view corresponding to Fig. 2, showing only the bolster and spring cap, said cap being shown in transverse section.

Figure 4 is a sectional view on the line 4—4, Fig. 3, looking in the direction of the arrows.

Figures 5 and 6 are sectional views on the correspondingly numbered lines in Fig. 3, looking in the direction of the arrows.

Figure 7 is a fragmentary view corresponding to Fig. 1, but showing a modification.

Figure 8 is a side elevation of the modified form of bolster and associated spring cap shown in Fig. 7.

Figure 9 is a plan of the spring cap illustrated in Figs. 7 and 8, the associated bolster being fragmentarily shown in horizontal section.

Referring to the drawings in detail, like parts being designated by like reference characters, and first considering the embodiment of my invention illustrated in Figs. 1 to 6, inclusive, there is shown a portion of a truck comprising a side frame 1 formed with a compression member 2, a tension member 3, and bolster guide columns 4 spacing intermediate portions thereof and spaced to leave a window opening 5 therebetween. In the present embodiment, the side frame illus-

trated is of the type described and claimed in my Patent No. 1,652,808 of December 13, 1927, on a car truck; but it is obvious that I do not wish to be limited to the embodiment of my 5 invention with such a type of frame, the showing being merely preferred but not limiting.

As more fully described in my prior patent, the side frame 1 involves auxiliary tension members 6, which cut across the lower corners 10 of the window or bolster opening 5 and form upwardly extending convolutions which strengthen the frame and serve for interlocking the spring plank 7 with respect thereto, said spring plank being for that purpose provided 15 with corresponding upwardly extending convolutions or corrugations 8. Resting on said spring plank are a plurality of bolster springs 9, said springs being preferably arranged as disclosed in my above referred 20 to patent, and provided with spring plates 10 and 11, although I do not wish to be limited to such specific disclosure of the springs. Resting on the tops of the springs or top 25 spring plate 11 is a spring cap 12 preferably provided with outwardly extending flanges 13 and 14, the inner flanges 14 being reduced in height to facilitate insertion and withdrawal of said cap through the widened portion of the window opening immediately 30 above the auxiliary tension portions 6, said flanges 13 and 14 extending outwardly and embracing the adjacent portions of the bolster guide columns 4 where the same extend closer together in the upper portion of the 35 window opening.

The lower surface of the spring cap 12 is preferably generally flat but provided with depending peripheral flanges 15 which are adapted to embrace the tops of the springs 40 9 and assist in maintaining them in desired position. The upper surface of the base or lower web 16 of the spring cap is preferably generally curved convexly upward to permit rocking or rolling between said cap and the 45 associated bolster 17, although as an alternative the engaging surface of the bolster may be curved and the upper surface of the web 16 of the spring cap flat or of less curvature than that of the bolster.

50 In the embodiment illustrated the guiding flanges 13 and 14 are connected by side walls 18 which extend around the end of the bolster and serve as a limit stop therefor in the front 55 of the cap but are omitted at the rear of the cap to prevent interference with said bolster, thereby providing a depressed seat for the bolster on top of the web 16. For preventing longitudinal displacement of the bolster on the spring cap the upper surface of the web 60 16 thereof is preferably formed with an upstanding tooth or boss 19 and the lower surface of the bolster correspondingly pocketed as indicated at 20, for receiving said tooth 19. In order to interlock the bolster with respect to the side frames, only one of which is illus-

trated, the ends thereof are provided with downwardly opening depressions or pockets 21 receiving a corresponding rib or boss 22 on each spring cap. On account of this construction the bolster 17 is interlocked with respect to the spring cap 12 both longitudinally and transversely, and as said cap is likewise interlocked with respect to the frame said bolster is properly interlocked with respect to the side frame without being provided with the usual guiding flanges for directly engaging the guide columns of the frame.

In the present embodiment, the bolster illustrated comprising an angular or channel' shaped compression member 23 spaced from a tension member 24, which is preferably flat, at intermediate portions thereof in any usual or desired manner, not shown, with the ends of said members connected by having the 85 ends of the tension member extending between the depending flanges 25 of the compression member and seated on the under surface of the web 26 thereof, said web preferably being bent upwardly to aline it with the inclined ends of the tension member 24. The ends of the tension member may be upset to provide shoulders as indicated at 27 for engaging the ends of the compression member 90 in order to more firmly connect said parts. Seated on the ends of the tension member and adjacent the junction between compression and tension members is an end casting 28 which is that part of the bolster carrying the pockets 20 and 21 for interlocking the same 95 with respect to the spring cap. Said compression member, tension member and end casting 28 are preferably connected together by common rivets 29 extending through the web of the compression member, the tension 100 member and the adjacent web of the end casting. Although only one end of the bolster is illustrated it is obvious that the other end is preferably formed to correspond and is similarly connected to the other associated 105 side frame and supported parts. In order to firmly connect the end castings 28 to the beam portions of the bolster not only are the common rivets 29 employed extending 110 through the compression, tension and end casting portions, but said end castings are preferably formed with depending flanges 115 30 which lie along the inner sides of the flanges 25 of the compression member 23 and are connected thereto by rivets 31. On account of this construction the parts of the bolster are very firmly secured together to give a structure which is comparable to a cast bolster such as will now be described.

Referring now to the modification of my 125 invention illustrated in Figs. 7, 8 and 9, a side frame 1^a is there disclosed which is formed with a compression member 2^a, bolster guide columns 4^a, and a tension member not shown defining a window opening 5^a, as 130

in the previous embodiment. Although the frame is only fragmentarily illustrated, it will be understood that it may be identical with the frame of the first embodiment and the bolster springs 9^a may be supported in the same manner.

Resting on the springs 9^a or the upper spring plate 11^a if used, is a spring cap 12^a formed with outstanding flanges 13^a and 14^a which embrace the adjacent portions of the guide columns and hold the cap in proper relation with respect to the frame while permitting up and down movement thereof with variation in the load on the associated bolster 17^a. As in the previous embodiment, the spring cap preferably has depending peripheral flanges 15^a extending from the lower web 16^a thereof and the guiding flanges 13^a and 14^a are connected by guide column engaging webs 18^a, said webs, however, being preferably not continued around the end of the bolster as in the previous embodiment, no limiting stop of this character being necessary as the present bolster is narrowed where it extends between the webs 18^a whereby shoulders 32 are provided for limiting the outward movement of the bolster with respect to said webs 18^a and associated flanges.

As in the previous embodiment, the upper surface of the web 16^a of the spring cap is preferably curved or formed of such a shape compared with the engaging surface on the bolster that rocking movement between the members is permitted. As previously described in connection with the first embodiment, a boss or tooth 19^a is provided engaging in a corresponding pocket or cavity 20^a in the bottom of the bolster 17^a, thereby retaining said bolster in proper position with respect to the spring cap longitudinally of the frame. For interlocking the bolster with respect to the spring cap transversely of the frame, said cap is preferably formed with an upstanding longitudinally extending boss or rib 22^a which is received in a corresponding pocket or groove 21^a formed in the lower portion of the bolster, whereby said bolster is not only interlocked longitudinally but also transversely with respect to said spring cap.

As in the previous embodiment, sufficient clearance is provided between the top of the rib 22^a and the top wall of the pocket 21^a to permit the desired vertical rocking between the bolster and spring cap, but as distinguished from the first embodiment, the rib 22^a preferably flares or is inclined outwardly and upwardly toward the sides of the spring cap whereby the average height thereof is considerably increased as distinguished from the first embodiment in which there is only a very slight incline of this rib. One reason will be apparent for the slight incline in the first embodiment, and that is the depth of the end casting on the built up bolster 17 is less than the depth of the bolster 17^a which, in the

present embodiment, is of integral cast construction. A further difference, that will be noted in the present embodiment, is that the rib 22^a and the corresponding pocket 21^a is approximately axially disposed with respect to the associated side frame, whereas in the first embodiment it was offset outwardly thereof on account of the tapering character of the end casting 28 in order to be positioned in a portion of said end casting of sufficient height. Except as specifically described in connection with the present embodiment the same may correspond substantially with that of the first embodiment.

From the foregoing description, taken in connection with the accompanying drawings, it will be seen that I have devised a railway truck which provides for rocking between the side frames thereof and the associated bolster by providing a spring cap associated with said side frames, the upper surface of which is so formed and interlocked with respect to the lower surface of the associated bolster that relative angling therebetween in vertical longitudinal planes is permitted.

The bolster employed may be either one of the built up type, as illustrated in the first embodiment, or of integral cast construction, as illustrated in the second embodiment, and is preferably though not necessarily interlocked with respect to the side frame indirectly through the associated spring cap, having notches or pockets in the lower portions of the ends thereof engaging corresponding ribs or bosses extending both longitudinally and transversely whereby said bolster is locked in both directions with respect to said cap.

In order to permit the desired rocking between the bolster and the associated caps at either end thereof, the necessary amount of clearance is provided between the tops of the longitudinal ribs on the spring caps and the top walls of the corresponding pockets in the bolster. In order to facilitate insertion and removal of the spring caps the column engaging flanges thereof at one side of the frame, preferably the inner side, are formed shorter than those on the other side whereby they are freely insertable above the auxiliary truss or tension portions of a double truss side frame such as disclosed in my Patent No. 1,652,808, previously referred to.

Although I have described and claimed a bolster of the Hunton or built-up type in combination with devices for permitting longitudinal rocking in vertical planes between said bolster and the side frames, it is obvious that I do not wish to be limited to such construction, as, if desired, such a bolster may be used, not only with devices permitting rocking, but also with devices permitting lateral motion of the bolster with respect to said side frames, or with such lateral motion devices without the rocking feature, such as described and claimed in my companion ap-

plication Serial No. 256,332, filed February 23, 1928.

Having now described my invention, I claim:

5. 1. A railway truck having side frames and a bolster connecting said frames, said bolster being formed to permit relative rocking of said frames in longitudinal upright planes and notched on its lower surface for interlocking connection therewith.
10. 2. A railway truck having side frames formed with a bolster opening, springs supported in said bolster opening, a spring cap supported on said springs and interlocked with respect to said frame, and a bolster resting on said spring cap, the engaging surfaces of said bolster and cap permitting relative rolling between said members in vertical longitudinal planes.
15. 3. A railway truck having side frames formed with bolster openings, bolster springs in said openings, springs caps supported on said springs and formed with interlocking flanges engaging the frames at the sides of said openings, a bolster supported on said spring caps and interlocked to limit transverse movement therebetween, the engaging surfaces between said bolster and spring caps being formed to permit longitudinal rocking between the parts.
20. 4. A railway truck having side frames formed with compression and tension members, bolster guide columns connecting intermediate portions of said compression and tension members and spaced to leave a bolster opening, bolster springs supported by means of said tension member in said opening, spring caps supported on said springs, said spring caps having upstanding side portions interlocked with respect to the guide columns, a bolster supported on said spring caps between said side portions, said bolster being formed with notches in the engaging surfaces for receiving corresponding projections on said spring caps for interlocking said bolster and spring caps longitudinally and transversely, some of the engaging surfaces between said bolster and spring caps being curved to permit relative rocking therebetween.
25. 5. In a railway truck, a side frame formed with compression and tension members, bolster guide columns connecting intermediate portions of said members, bolster springs supported by means of said tension member between said bolster guide columns, a spring cap supported on said springs, said spring cap being formed with flanges interlocking with said bolster guide columns for retaining said cap in place, the flanges on one side of said frame being shorter than those on the other to permit ready insertion or withdrawal of said spring cap, and a bolster supported on said spring cap and interlocked with respect thereto.
30. 6. In a car truck, in combination, a side frame comprising a compression member, a tension member, bolster guide columns interposed therebetween and spaced to leave a window opening, the construction adjacent the junctions between the bolster guide columns and tension member being reinforced by auxiliary diagonal tension members which cut across the lower corners of the bolster opening, bolster springs supported by means of said tension member, a spring cap supported on said bolster springs and formed with flanges embracing the adjacent portions of the bolster guide columns for retaining said cap in place, said flanges disposed inwardly of said frame being reduced in height to facilitate insertion and withdrawal over the auxiliary diagonal tension members, and a bolster supported on said spring cap and interlocked with respect thereto.
35. 7. A railway truck having side frames and a bolster connecting said frames, said bolster comprising an angular compression member, a tension member riveted thereto and extending therebeneath, and cast end pieces connected adjacent the ends of said compression and tension member with their under surfaces formed to permit relative rocking of said frames in longitudinal upright planes.
40. 8. A railway truck formed with side frames and a bolster connecting said frames and received at its ends in bolster openings therein, said bolster being formed with a compression member, a tension member, cast end pieces and common rivets extending through said end pieces, compression and tension members, the lower surfaces of said end pieces being notched for interlocking said bolster with respect to the associated parts of side frames.
45. 9. A railway truck having side frames each formed with a bolster opening, springs supported in said bolster opening, a spring cap supported on said springs and interlocked with respect to said frame, and a bolster resting on said spring cap, said bolster comprising an angular compression member and a flat tension member, the ends of said compression and tension members being riveted together and to end castings, each end casting resting on a spring cap, the engaging surfaces of said end casting and cap permitting relative rocking between said frames and bolster in vertical planes.
50. 10. A railway truck having side frames formed with bolster openings, bolster springs in said openings, springs caps supported on said springs and formed with interlocking flanges engaging the frames at the sides of said openings, a bolster supported on said spring caps and comprising end castings interlocked with said caps to limit transverse movement therebetween, and compression and tension members connecting said end castings and connected together at their ends, 125 130

the engaging surfaces between said end castings and caps being formed to permit longitudinal rocking between the parts.

11. A railway truck having side frames formed with compression and tension members, bolster guide columns connecting intermediate portions of said compression and tension members, and spaced to leave a bolster opening, springs supported by means of said tension member in said opening, spring caps supported on said springs and interlocked with respect to said guide columns, a bolster supported on said spring caps and comprising a compression member, a tension member and end castings connected to said compression and tension members by rivets extending therethrough, said end castings being formed with notches in the engaging surfaces for receiving corresponding projections on said spring caps for interlocking said bolster and spring caps longitudinally and transversely, some of the engaging surfaces between said end castings and spring caps being curved to permit relative rocking therebetween.

12. In a railway truck, a side frame formed with compression and tension members, bolster guide columns connecting intermediate portions of said members, springs supported by means of said tension members between the bolster guide columns, a spring cap supported on said springs and formed with flanges interlocked with said bolster guide columns for retaining said cap in place, the flanges on one side of said cap being shorter than those on the other to permit ready insertion and withdrawal of said cap, and a bolster supported on said cap and comprising a built up intermediate portion and cast portions connected at the ends thereof, one of said cast portions being interlocked with respect to said spring cap.

13. In a railway truck, in combination a side frame comprising a compression member, a tension member, bolster guide columns interposed therebetween and spaced to leave a window opening, the construction adjacent the bolster guide columns and tension member being reinforced by auxiliary diagonal tension members which cut across the lower corners of the bolster opening, a spring plank resting on said tension member beneath the bolster opening and interlocked with respect to said auxiliary tension members, spring means supported on said spring plank, a spring cap supported on said spring means and formed with flanges embracing the adjacent portions of the bolster guide columns for retaining said cap in place, said flanges disposed inwardly thereof being reduced in height to facilitate insertion and withdrawal over the auxiliary tension members, and a bolster formed with an end casting supported on said spring cap and interlocked with respect thereto.

14. A railway truck having a side frame

formed with a bolster opening, a spring plank supported in said opening, bolster springs supported on said spring plank, a spring cap supported on said springs and formed with interlocking flanges engaging the frame at the sides of said opening, a bolster supported on said spring cap and interlocked with respect thereto to limit transverse movement thereof, the engaging surface between said bolster and spring cap being shaped to permit longitudinal rocking between the parts.

15. A railway truck having a side frame formed with compression and tension members, bolster guide columns connecting intermediate portions of said compression and tension members and spaced to leave a bolster opening, a spring plank supported on said tension member beneath the bolster opening, bolster springs supported on said spring plank, a spring cap supported on said springs and interlocked with respect to the guide columns, a bolster supported on said cap and formed with notches in the engaging surface for receiving corresponding projections on said cap for interlocking said bolster and cap longitudinally and transversely, one of the engaging surfaces between said bolster and cap being curved to permit relative rolling therebetween.

16. A built up bolster comprising an angular compression member, a flat tension member and end castings, said compression and tension members being connected together and to the end castings by common rivets, said end castings being formed with their under surfaces notched for interlocking with associated side frames.

17. A bolster formed with notches in the lower surfaces of the ends thereof adapted to interlock with associated spring caps, said notches extending longitudinally and transversely for interlocking said bolster in both directions and formed of approximately the same depth at the point of intersection.

18. A built-up bolster comprising a channel compression member, a flat tension member, the ends of said tension member being received against the web of the channel member and between the flanges thereof, and end castings, said compression and tension members and end castings being connected together by common rivets passing through the web of the compression member, said end castings having their under surfaces formed with intersecting notches for interlocking said bolster both longitudinally and transversely with respect to associated side frames.

In testimony whereof I affix my signature.
DONALD S. BARROWS.
